US0D1083405S

(12) **United States Design Patent** (10) Patent No.: **US D1,083,405 S**
(45) Date of Patent: ** Jul. 15, 2025

(54) **THERMOSET SURFACE MATERIAL WITH ORNAMENTATION**

(71) Applicant: **DUPONT SAFETY & CONSTRUCTION, INC.**, Wilmington, DE (US)

(72) Inventor: **Massimo Fucci**, Milan (IT)

(73) Assignee: **DUPONT SAFETY & CONSTRUCTION, INC.**

(**) Term: **15 Years**

(21) Appl. No.: **29/779,561**

(22) Filed: **Apr. 20, 2021**

(51) LOC (15) Cl. **05-06**

(52) U.S. Cl.

USPC **D5/44**; D25/151

(58) **Field of Classification Search**

USPC D5/1, 2, 4, 7, 8, 12, 15, 27, 29, 30, 32, D5/35, 36, 37, 43, 44, 47, 48, 53, 55, 56, D5/57, 58, 59, 60, 61, 62, 63, 64, 66, 99; D6/610, 613, 616; D19/5; D20/22, 27; D25/138, 149, 151; D32/57

CPC E04D 13/031; B05D 1/20; B32B 25/045

See application file for complete search history.
